UNITED STATES PATENT OFFICE

JOSHUA BARTON HARRY, OF PHILADELPHIA, PENNSYLVANIA

COOLING TOWER

Application filed December 22, 1928. Serial No. 327,945.

This invention is concerned with improvements in cooling towers, adapted for use in cooling condenser water, in power plants, etc., and is directed more particularly to new and useful improvements in the elements of the tower, and in combinations of the same.

An object of the invention then, is to produce an improved form of cooling tower.

Another object is to construct a new form of louver, for preventing the escape of the water without unduly obstructing the circulation of air, and brackets for the same.

Another feature of the invention comprises a new, substantially W-shaped, metal drip bar.

Still another feature is resident in a wooden drip bar, having top, side, and bottom grooves, providing for uniform flow of water, and spacing means therefor.

Yet another feature is a drip bar having top and bottom grooves, and set on edge, to give strength, the edges of each bottom groove providing two longitudinal drop surfaces.

Another feature comprises end and intermediate spacing bars for the last-mentioned drip bars.

Other objects will be evident in view of the accompanying disclosure, illustrating one form of the invention, and from the appended claims.

In the drawings:

Fig. 1 is a vertical section of the assembled cooling tower depicting the elements situated in their respective places;

Fig. 2 is a detailed, partly drop perspective of the metal drip bars in assembled relation with one form of wooden drip bar, parts being shown in section, and a spacer for the wooden drip bars also being shown;

In Fig. 3, is a perspective view showing the parts of the louver detached;

Fig. 4 is a detailed perspective view of the arrangement of the wooden drip bars shown in the lower portion of Fig. 1;

While Figs. 5 and 6 are perspective views of the details of the spacers shown in Fig. 4.

At 1 is shown a pan-like base, which serves the double function of catching the drip water from the nozzles 2, 2, and of acting as a support for the frame of the apparatus. The

frame in the present instance is rectangular in plan, but it will be understood that the shape of the frame may be modified without departing from the essential feature of the invention.

At 3, 3 are shown two of four or more vertical supports on which are carried the louvers 4 and louver brackets 5. These louvers which are ordinarily on all four sides of the tower, serve to prevent the escape of the cooling water and at the same time, avoid undue retardation of the air flow. Suitable means, not shown, are preferably provided to prevent objectionable rattling of the louvers, and the lowermost edges 4a of the louvers are nested closely against the inside edge 5a of the brackets, to facilitate this silencing action.

From nozzles 2, the water to be cooled flows first over the W-shaped drip bars 6, and thence to another series of drip bars 7, disposed substantially at right angles to bars 6.

Movement of members 6 and 7 is prevented by means of a suitable clamp 8, which clamp the elements firmly against the lower framework.

From the drip bars 7 the water trickles over a drip bar system 9, comprising two series of bars 10 and 11, arranged longitudinally of one another with ends of the bars of one series overlapping the bars of the other series (Fig. 4).

In Fig. 2 it will be noted that the W-shaped drip bar 6, of metal, has a central portion 12 somewhat higher than the wings 13, 13, the edges of which are crimped as at 14.

The tops of these crimped edges are substantially on a line with holes 15 on the center portion of the bar.

At each end of the bars 6 are metal closure plates 16, which, in combination with the valleys of the bars, define troughs.

The high central portion 12 serves as a splash plate, deflecting the stream from the nozzles 2 to both sides, thus materially increasing the wetted surface of the bar, and resulting in efficient heat dissipation, while the holes 15 permit a uniform flow over the under portions of the bar, and expose them to the upper air currents.

The position of the crimped edges 14 permits water to overflow them at the same time it flows through the holes 15.

In this manner the entire surface of the 5 drip bar 6 is wetted with the exception of the small inside portion above the holes at the center.

The three bends and the crimped edges of the bars 6 give them much greater strength 10 and rigidity than metal drip bars now on the market.

Immediately below the series of metal drip bars and arranged with their longitudinal axes transverse thereto, are a plurality of 15 wooden drip bars 7.

These drip bars 7 are each provided with a longitudinal trough 17 on the upper surface; a trough 18, diagonally inset on one side, and also extending longitudinally thereof; and 20 two slots 19 on the under side, each of these slots being provided with closed ends.

Water, trickling over from the drip bar 6, collects in the trough 17. Upon the overflow of 17, the water trickles over into trough 25 18. But little, if any splashing accompanies this action, due to the diagonal arrangement of trough 18. The troughs 19 catch the water in two beads on the bottom of the bar and permit it to drop off along two lines, thus 30 doubling the drop surface.

A spacing member 20 of approximately 35 channel section has its rear depending flange 21a abutting the ends of the bars, while its front flange is cut away to provide arcuate projections 21 to properly space the bars 7 with respect to one another, the projections 21 fitting the ends of the troughs 17. A bolt hole 22 is provided on the upper surface of member 20, to provide clamping means there- 40 for.

As is readily apparent these bars are quite rigid and durable.

As has been said before, any suitable type 45 of clamping means may be used to clamp the bars 6 and 7 in position.

As shown, one form of such means comprises a yoke 23, provided with a V-shaped opening for the reception of the middle section of the bar 6, and provided with bolt holes 55 24, adjacent each end for the reception of bolts 24, between the heads 25 of which and the yoke 23 are the washers 26. These bolts extend one on each side bar 6, and between adjacent bars 7, being locked underneath the 55 last-mentioned bars by means of lock nuts 27 and washers 28.

A number of such clamping means are provided for each drip-bar 6.

The water trickles from the bars 7 to a 60 number of intermediate decks of drip bars, one of which is shown at 9 in Fig. 1, and in greater detail in Fig. 4. The decks are arranged with the bars of one deck extending at right angles to the bars of the adjacent 65 decks.

These drip bars 9 are preferably cut from a solid piece of wood preferably cypress, and are stood on edge, having grooves on the upper and lower surfaces, shown in the drawings as being of V-section.

The fact that these members are stood on edge forms a very great advance in the art. Where wood slats have been used as cooling surfaces in the past, they have been laid flat or stood at an angle. When used in this manner the slats are quite weak, and have considerable sag. With my construction a well-known method of lending rigidity is employed in a cooling tower for the first time.

As will be seen, such a deck here consists of 80 two series 10 and 11 of the bars described, the ends of which in one series slightly overlap the adjacent ends of the bars of another series.

Each series is provided with end spacing 85 and clamping members 29. These members comprise a top surface 30, from the underneath of which downwardly extend spacing lugs 31. These lugs are substantially the width of a bar, and extend between adjacent 90 bars. Cooperating with the bars in the other series, these lugs cause all the bars to extend in substantially parallel longitudinal planes.

Also provided underneath the upper surface 95 30 are lugs 32, corresponding in shape to the cross section of the grooves of bars 10, 11. When the members 29 are fitted in position, the lugs 32 fit into the grooves, closing them, thus creating a trough effect, and causing the water to traverse a large area of cooling 100 surface.

Intermediate spacers 34 are provided, as shown in Figs. 4 and 6. These spacers are also provided with a plurality of centrally located lugs 32a, the quantity being doubled 105 over that of element 29, inasmuch as there are twice as many bars to space.

These lugs are preferably centrally located except where the bolt hole 33 is provided. At 110 this point the lugs are placed on each side of the bolt hole, as at 36. A conventional clamping means 35 is also used to retain spacer 34 in position. Each border of each trough defines a drop surface, from which the water leaves the lower edge of the drip bar, the surface of which it has followed due to the attraction thereto. Thus each drip bar defines a plurality of drop surfaces, resulting in considerable economy of operation.

In Fig. 3 are shown the details of the louver and louver brackets. Each louver is corrugated for the purpose of lending rigidity to the structure, and is loosely fitted in end brackets 5, 5 which are bolted directly to the tower framework. Considerable advantage results from this structure, inasmuch as in the past it has been the custom to punch the louvers at either end and bolt them directly to frame. It is at these punch holes, which 120

tend to weaken the louvers, that corrosion starts; and by my construction, these starting points have been eliminated. As has been pointed out before, suitable means are 5 preferably employed to prevent the louvers from rattling, the particular arrangement of the louver edge 4a with respect to the inner surface 5a of the louver bracket facilitating this action.

10 By my construction it is also possible for the louvers to slide in either direction, thus compensating for expansion and contraction; one of the previous serious problems of cooling tower manufacturers.

15 The operation is as follows:

The heated water from the nozzles 2 trickles over the bars 6 to 7, thence to decks of bars 9. These bars are designed to have as large a portion of their surface as possible wetted by the water. In its progress from deck to deck the water is cooled by flow of air through the decks. As a result, the water, when it reaches the bottom of the tower, is cooled to a point where it can be returned 25 to the system to again act as a cooling medium.

A particularly novel feature of my invention is resident in the provision of a large amount of unobstructed vertical air column, 30 providing a very efficient flow of air. For instance, in the lower series of drip bars, there are seven vertical openings 37 to the foot of deck width, each opening being approximately $\frac{13}{16}$ " in width and about three or four feet in length. In addition, the drip bars are arranged in such a manner as to produce a central, unobstructed air column 38 which is about 18" wide, and which extends substantially the full height and entire length of the 40 tower. The incoming hot water supply pipe 39 insures that a proper draft is supplied for the central opening.

While but one form of my device has been disclosed, a number of modifications will be 45 obvious to one skilled in the art, and it is intended that my invention shall be limited only by the scope of the appended claims.

I claim:

1. In a cooling tower system, the combination of a series of drip bars having their longitudinal axes parallel, each bar having a longitudinal trough on its upper surface, and a spacer of approximately channel section, extending transversely of the longitudinal axes of the bars; the outer flange of said spacer extending downwardly therefrom and abutting the ends of said bars, the inner flange of the spacer being cut away to form spacing lugs of contour substantially that of the section of the troughs, and fitting therein adjacent the said ends of the bars.

2. In a cooling tower, a series of wooden drip bars having longitudinal grooves arranged centrally in their edge surfaces, and 60 being placed on their edges, and a spacing

element therefor, resting on top of said bars and having a series of downwardly extending lugs to fit between and space the bars, and another series of downwardly extending lugs adapted to fit in the grooves of the bars, and 70 to cooperate therewith to define troughs.

3. In a cooling tower a series of drip bars stood on edge with their longitudinal axes parallel, longitudinal grooves extending centrally of the edges of said bars; said bars being spaced from one another by a distance approximately that of the width of the edge of one bar; and another similar series of drip bars, forming a substantial continuation 75 of said first series but staggered with respect thereto by a small amount, the bars of the second series slightly overlapping the first series; and a spacing and clamping element therefor, comprising a main top portion, resting on the overlapping portions of the bars; 80 and lugs extending downwardly therefrom, the contours of which conform to that of the sections of said grooves, fitting into said grooves, thereby defining a series of troughs.

4. In a cooling tower, a series of drip bars 90 having grooves therein, and spacers therefor each having a main body portion from which a plurality of lugs extend downwardly, said lugs having a contour similar to that of said grooves, in order that they may snugly fit 95 therein and means clamping the spacers to the bars whereby the lugs are brought into sealing engagement with the walls of the groove to provide a dam sealing the end of the groove.

5. In a cooling tower system, means for spraying water, a series of drip bars of substantially W-shaped section arranged therebeneath, another series of drip bars clamped underneath the first-named series, and arranged at right angles thereto, and having troughs on three surfaces of each bar, a plurality of series of drip bars arranged under said second series, each of such plurality of series extending transversely of adjacent series, the individual bars of the last-mentioned type of series being placed on edge and a plurality of corrugated louvers arranged on the vertical walls of the tower for controlling the flow of air over the drip bars.
